UNITED STATES PATENT OFFICE.

LEWIS ROBERT DORAN AND ARTHUR TAGGART, OF GLASGOW, SCOTLAND.

STEAM-ENGINE INDICATOR.

SPECIFICATION forming part of Letters Patent No. 655,857, dated August 14, 1900.

Application filed March 20, 1900. Serial No. 9,436. (No model.)

To all whom it may concern:

Be it known that we, LEWIS ROBERT DORAN, residing at Gallowflat House, Rutherglen, Glasgow, and ARTHUR TAGGART, residing at 5 30 Sutherland Terrace, Glasgow, Scotland, citizens of the United Kingdom of Great Britain and Ireland, have invented certain new and useful Improvements in Steam-Engine Indicators, (for which application for patent 10 has been made in Great Britain, No. 18,227, dated September 9, 1899,) of which the following is a specification.

This invention relates to improvements in indicators for steam or other engines, and has 15 for its objects to facilitate the changing of the diagram-cards, especially when running at high speed, and also to provide more efficient means for multiplying the motion imparted to the recording-pencil.

20 The invention is illustrated by the accompanying drawings.

Figure 1 is a vertical section of our improved indicator, and Fig. 2 a plan of the same with the cylinder-cover and parallel motion 25 removed.

In accordance with our invention the paper-drum A and the cord-drum B are separate from each other and are mounted upon the central supporting-spindle C in the same relative positions to those of existing indicators, each being under the influence of an independent spring A' B', respectively. The cord-drum B is rotated in the usual way, and the paper-drum A is driven therefrom by a pin 30 or stud E, arranged in the path of a pin or stud F on the cord-drum B. In order that a new card may be placed around the paper-drum A while the cord-drum B is connected to the engine, the lower end of the paper-drum 35 40 A is provided with teeth A' to receive a detent in the usual way; but in place of employing an ordinary detent, which causes the paper-drum A to receive a shock when the stop of the cord-drum B lifts it off at each stroke, and thus adds to the difficulty of getting on 45 a card, we may employ a detent or pawl G, acted upon by a flat or other spring H, which normally holds it out of action, and centered at G' on a ring sleeve or collar I, capable of 50 being rotated or partially rotated around the outside of the cylinder K by a knob or han-

dle J to bring it into action. In order to arrest the paper-drum A, the aforementioned collar or sleeve I is rotated to the position shown by the dotted lines, Fig. 2, causing the 55 detent or pawl G to engage with one of the teeth A' and by its continued rotation in a direction opposite to that exerted by the springs removes the pin E of the paper-drum out of the reach of the cord-drum pin F. The 60 sleeve I may, as shown, be retained in position by a horseshoe-shaped ring M, situated above the sleeve I and entering an annular groove K' in the cylinder K, which latter may also be formed with stops or projections K² 65 for regulating the extent of travel of the sleeve I. To restart the paper-drum A, the sleeve I is returned to the position indicated in full lines, Fig. 2, which shows the detent G just leaving the teeth A'. This latter movement 70 insures the drum A starting without shock, as the detent G is not released from the teeth A' of the paper-drum A until the tension of the latter's spring A' is being borne by the pin F of the cord-drum B. Further, in order 75 that the motion imparted to the recording-pencil may be more efficiently multiplied, we pivot the pencil-carrying arm R to a short link O, which in turn is pivoted or hinged to a standard or stationary arm P, mounted upon 80 any convenient part of the indicator. A pair of toggles or hinged links Q R are pivoted, respectively, to the before-mentioned standard P and to a point N' upon the pencil-carrying arm, the arrangement resembling a "lazy- 85 tongs" and being such that when one of the toggles Q is subjected to a very slight motion from the piston S through the piston-rod S' and connecting-link T a very considerable motion is given through the toggle R to the 90 pencil-arm N, thus producing a diagram of greater exactitude. One of the toggles, preferably the toggle R, may be fitted with a pin or projection R', arranged to work in a guide T of suitable form for the purpose of securing 95 a perfectly-vertical motion.

With this indicator also we may attach the end of the spring V to the piston S within the cylinder K by passing the end thereof through an aperture formed in a stud W, attached to 100 the piston S and screwed into the end of the piston-rod S', thus lightening the weight of

the moving parts. The end of the spring W may be retained in position by brazing or otherwise.

Having now described the invention, what 5 we claim, and desire to secure by Letters Patent, is—

1. An indicator for steam or other engines comprising a cord-drum, an independent paper-carrying drum having a series of teeth 10 thereon and mounted upon the same spindle as the cord-drum, springs controlling these drums, a pencil-carrying arm arranged in proximity to the paper-drum and forming one element of a parallel motion consisting of a link 15 jointed to said pencil-arm and to a stationary standard, a pair of toggle-links connected to the standard and to the pencil-arm, and also connected by a short link to the piston-rod and a detent or pawl centered on a movable collar or sleeve capable of being rotated 20 to bring said detent into engagement with a series of teeth on the paper-drum, substantially as and for the purpose set forth.
2. In an indicator for steam or other engines, the combination with a paper-drum 25 having a series of teeth thereon, and mounted on a central spindle, of a spring for controlling said drum, a stud or pin secured in the paper-drum, a cord-drum independent of 30 the paper-drum, a spring for controlling the cord-drum and a pin or stud therein in engagement with the paper-drum, so that the paper and cord drums normally rotate together, a detent or pawl adapted to engage 35 the teeth on the paper-drum, a movable collar or sleeve on which said detent or pawl is centered capable of being rotated to bring the

detent into engagement with the teeth upon the paper-carrying drum, to turn said drum to such a position that its stud is held out of 40 the path of the pin on the cord-drum, and a spring bearing on said pawl and normally holding it out of engagement with the teeth, substantially as and for the purpose set forth.

3. In an indicator for steam or other engines, the combination with a rotating paper-drum of a parallel motion consisting of a pencil-carrying arm, a link connecting said pencil-arm to a stationary standard, a pair of toggle-links connected to said standard and 45 to the pencil-arm, a guide-pin on one of the toggle-links, a stationary guide in which said pin moves, and a short link connected to the other toggle-link and to the piston-rod, substantially as and for the purpose set forth. 50

4. In an indicator for steam or other engines, the combination with a paper-drum having a series of teeth thereon, of a detent or pawl, a movable collar or sleeve on which said detent or pawl is centered capable of being rotated to bring the detent into engagement with the teeth upon the paper-carrying drum, and a spring bearing on said pawl and normally holding it out of engagement with the teeth, substantially as and for the purpose set forth. 55

In witness whereof we have hereunto set our hands in presence of two witnesses.

LEWIS ROBERT DORAN.
ARTHUR TAGGART.
